US0D1041649S

(12) **United States Design Patent** (10) **Patent No.:** **US D1,041,649 S**
(45) **Date of Patent:** **** Sep. 10, 2024**

(54) **TRANSDERMAL APPLICATOR**

(71) Applicant: **PassPort Technologies, Inc.**, San Diego, CA (US)

(72) Inventors: **Harshal Shah**, Braintree, MA (US); **Kaitlyn Delaney Mary Leidl**, Cambridge, MA (US); **Karen Unterman**, Brookline, MA (US); **Gregg R. Draudt**, Stow, MA (US); **William J. Vespa**, Revere, MA (US); **Amy Lee Stockslager**, Cambridge, MA (US)

(73) Assignee: **PassPort Technologies, Inc.**, San Diego, CA (US)

(**) Term: **15 Years**

(21) Appl. No.: **29/854,689**

(22) Filed: **Sep. 27, 2022**

(57) **CLAIM**

The ornamental design for a transdermal applicator, as shown and described.

DESCRIPTION

FIG. 1 is a top perspective view of a transdermal applicator; FIG. 2 is a front view of the transdermal applicator of FIG. 1; FIG. 3 is a rear view of the transdermal applicator of FIG. 1; FIG. 4 is a right side view of the transdermal applicator of FIG. 1; FIG. 5 is a left side view of the transdermal applicator of FIG. 1; FIG. 6 is a top view of the transdermal applicator of FIG. 1; and, FIG. 7 is a bottom view of the transdermal applicator of FIG. 1.

In the drawings, the dashed broken lines and unshaded surfaces bound by broken lines represent features that form no part of the claimed design.

1 Claim, 6 Drawing Sheets
